UNITED STATES PATENT OFFICE

AMATO N. SAMMARONE, OF AKRON, OHIO.

BRUSH-HOLDER.

1,116,492.

Specification of Letters Patent. Patented Nov. 10, 1914.

Application filed January 31, 1914. Serial No. 815,687.

To all whom it may concern:

Be it known that I, AMATO N. SAMMARONE, a citizen of the United States, and a resident of Akron, in the county of Summit and State of Ohio, United States of America, have made certain new and useful Improvements in Brush-Holders, of which the following is a specification.

My invention is an improvement in brush holders, and has for its object to provide a device of the character specified, especially adapted for holding commutator brushes of electrical apparatus, wherein a holder is provided formed from two pieces of stamped metal, folded or bent in such manner as to provide a substantially box shaped holder having ways or guides to support the ordinary carbon brush for adjustment, and wherein resilient means is also provided 20 adapted to engage the brush to press it toward the face of the commutator.

In the drawings: Figure 1 is a perspective view of the improved holder, Fig. 2 is a top plan view, Fig. 3 is a longitudinal vertical section showing the brush in place, Fig. 4 is a plan view of the blank from which the fixed portion of the holder is formed, Fig. 5 is a similar view of the blank from which the movable portion of the holder is formed, 30 Fig. 6 is a perspective view of the tubular support for the spring, Fig. 7 is a similar view of the slide, Fig. 8 is a perspective view of the connection between the spring and the slide, and, Fig. 9 is a perspective view 35 of the spring.

In the present embodiment of the invention, the holder proper is formed from the stamped blanks shown in Figs. 4 and 5, one of the blanks forming the fixed portion 40 of the holder, and the other the movable portion. The blank shown in Fig. 4 comprises side wings or members 1 and 1^a, connected by a cross member or body 2, and each of the wings is provided with an extension 3 on the opposite side of the body from the wings. The extensions 3 are provided with openings 4, and each wing is provided with a circular opening 5 at its junction with the body, and at each of the said openings each wing 50 is provided with a marginal flange 5^a.

The blank is bent to cause the wings 1 and 1^a to lie in parallel spaced relation, and in vertical position, and at right angles to the body 2 which extends horizontally. The flanges 5^a of the openings 5 extend inwardly 55 toward each other, and are in register, and

the extensions 3 are bent to lap upon each other, and are secured together by rivets 6 which pass through the registering openings 4. The end of each of the wings 1 and 1^a 60 remote from the extension is flanged laterally inward, as shown at 7, and each of the wings is provided with a vertical slot 8 intermediate the flange 7 and the opening 5. The extensions 3 are provided with registering internally threaded openings, for receiving a set screw 9, for a purpose to be later described.

The blank shown in Fig. 4 comprises a body 10 and wings 11 and 11^a, and the wings 70 are bent at right angles to the body to lie parallel, and the body is of such length that when the wings are bent, as above mentioned, the movable portion of the holder will fit between the wings 1 and 1^a of the 75 fixed portion of the holder. Each of the wings 11 and 11^a is provided with a transverse opening 12 intermediate its ends, for registering with the slot 8 of the adjacent wing, and each wing is provided with an 80 arc-shaped series of teeth 13 arranged coaxial with the adjacent opening 12. Each wing is also provided with a vertical groove 14 on the opposite side of the opening 12 from the body, for receiving the adjacent 85 flange 7 of the fixed portion of the holder. The free end of each of the wings 11 and 11^a is bent laterally outward to form a guide or way 15, for a purpose to be presently described, and at the lower end of each guide 90 or way each wing is provided with a lug 95 which is bent at right angles to the guide or way to form a stop 16 for a purpose to be later described. The movable member of the holder is arranged between the wings 1 and 1^a of the fixed portion, and is movable vertically with respect thereto, the ribs 7 fitting in the grooves 14. A rod or shaft 17 is passed through the openings 12 and the slots 8 in register therewith, the ends 100 of the shaft or rod extending beyond each wing 1 and 1^a, and the ends of the shaft or rod are oppositely threaded, and are engaged by milled nuts 18. It will be evident that by loosening the nuts, the movable 105 member of the holder may be adjusted vertically with respect to the fixed member. The teeth 13 are bent laterally inward, as shown in Figs. 1, 2 and 3, to lie above the rod or shaft 17. The tubular support 19 shown in Fig. 6 is arranged between the 110 wings 11 and 11^a of the movable member,

and it will be noticed that each of the said wings 11 and 11^a is provided with an inwardly extending annular flange 20 at each of the openings 12, and the said flanges fit within the ends of the tubular support 19.

The resilient member shown in Fig. 9 is arranged on the tubular support 19, and the said member comprises a pair of coils 21 arranged co-axially with each other, and spaced apart at their inner ends. The resilient member is formed from a single rod or wire, which is first bent to form a cross bar 22 having at each end an eye or bearing 23, and each end of the spring is then bent to form the coil 21, the said coil being offset laterally from the cross bar and connected thereto by a portion 24 extending at right angles to the axis of the coils. Each extremity of the rod or wire is bent upwardly at right angles to the portions 24, as indicated at 25, and at the free end of each of the said portions 25 the rod or wire is bent into a substantially rectangular form to form a finger piece 26. The coils 21 are arranged on the tubular support 19, and the portions 25 of the spring are adapted to engage the teeth 13 or the body 10 of the movable portion of the holder. The brush 27 is supported by a slide comprising a plate 28 having at each end an inwardly extending flange 29 which overlies the adjacent face of the plate in spaced relation. The plate is also provided with an inwardly extending struck up lug 30, the said lug extending in the same direction as the flanges 29, and the free end of the lug is provided with an upstanding rib or flange 30^a. The plate is provided with an internally threaded opening 31 below the lug 30—30^a, for engagement by the threaded portion of a set screw 32. The brush 27 is provided with an opening through which the set screw extends, and the inner end of the screw engages the threaded opening 31 of the slide. The slide may be engaged with the movable portion of the holder from above, the flanges 29 of the slide engaging behind the flanges 15 of the wings 11 and 11^a. The stops 16 limit the downward movement of the slide. The upper end of the brush is flush with the upper edge of the slide, and a contact member comprising a split washer 33 and an integral socket 34 is held to the brush by the set screw, the set screw having an annular rib 35 for engaging the washer.

The washer is slipped over the threaded portion of the set screw, as indicated in Figs. 1 and 3, and by means of the said screw the contact member is clamped to the brush and the brush to the slide. The lower end of the brush is shaped to fit the commutator 3, and the resilient member shown in Fig. 9 is connected to the slide in such manner that the said resilient member acts to press the brush toward the commutator.

The spring is connected to the brush by means of a substantially S-shaped connector shown in Fig. 7. The said connector comprises a plate 37 having at its upper end a hook 38, and at its lower end a pair of 70 spaced open bearings 39. The body of the plate is cut away between the bearings as shown at 40, and the opposite end of the plate is notched or recessed, as shown at 41. A shaft 42 is passed through the eyes 23 of 75 the spring, and through the bearings 39 of the connector, to connect the said connector with the spring, and the upper end or hook 38 of the connector is engaged with the lug 30. The cut away portion 41 engages the 80 lug, and the depending portions at each end of the cut away portion engage the opposite side edges of the lug to prevent lateral movement of the connector. The body 2 of the fixed portion of the holder is provided with 85 a threaded opening at approximately its center, and a connector comprising a split washer 43 and an integral socket 44 is held to the body, by means of the set screw 45 shown in Figs. 1, 2 and 3. A flexible insulated conductor 46 has one end held in the socket 34, and the other end in the socket 44, thus connecting the brush directly with the body of the fixed portion of the holder. The usual supporting stud or rod for the 90 brush holder is passed through the registering openings 5, and the set screw 9 is threaded into engagement with the said rod or stud, to prevent angular movement of the holder with respect to the said stud or rod. 100

In operation, the fixed portion of the holder is arranged on the stud or rod, and the set screw 9 is turned to clamp the fixed portion of the holder to the said stud or rod. By loosening the nuts 18 the movable portion of the holder comprising the body 10 and the wings 11 and 11^a may be adjusted vertically, and may be held in adjusted position by tightening the said nuts. The slots 8 permit considerable adjustment without 105 disturbing the relative arrangement of the resilient member, its tubular support, or the connector. The slide to which the brush is connected moves on the guides or ways 15 of the movable portion of the support, and the 110 tension of the spring may be varied, by engaging the portions 25 of the spring with different teeth of the series 13. The spring acts at all times to press the body toward the commutator bars with the proper degree 115 of tension, and the wear of the brush will be uniform and even.

It will be obvious that a considerable reduction in the expense of manufacture is attained, by forming the holder from two 125 pieces of metal, each of which may be stamped to proper form, and afterward bent to shape. The holder as a whole is a simple yet effective means for so holding the brushes that they may be alined properly 130

with respect to the axis of the commutator, and will be supported for free sliding movement toward the commutator. Any desired degree of tension may be brought upon the brush to insure its most effective engagement with the commutator.

I claim:—

1. A commutator brush holder, comprising approximately parallel spaced wings 10 and a body connecting the wings at one end, each of the wings having an extension at the opposite side of the body from the wing, the extension overlapping and being secured together, each wing having an opening at its 15 junction with the body, and the openings being alined and being adapted to receive a supporting stud for the holder, the movable portion comprising a body extending transversely between the wings of the fixed 20 portion and wings fitting along the inner faces of the wings of the fixed portion, each wing of the fixed portion having an inwardly extending vertical rib at the end remote from the body, and each wing of the 25 movable portion having a groove for engagement by the adjacent rib, each wing of the fixed portion having a transverse opening intermediate its ends and an arc-shaped inwardly extending series of teeth at its 30 upper edge and co-axial with the adjacent opening, each wing of the fixed member having a vertical slot registering with the adjacent openings, a rod having its ends oppositely threaded passing through the slots 35 and the openings, a nut engaging each end of the rod for clamping the sections together, a tubular support on the rod engaging the wings at its ends, a spring comprising similar sections, each section having a 40 coil intermediate its ends fitting over the tubular support, and having an upwardly extending finger piece for engaging the teeth of the adjacent wing to permit the tension of the spring to be adjusted, each 45 spring having an extension at approximately a right angle to the finger piece, a holder for the brush having flanges for engaging behind the guides or ways, and a connector engaging at one end the extensions of the spring and at the other the 50 guide member.
2. A commutator brush holder, comprising a fixed member having a transverse opening for receiving a supporting stud 55 for the holder, a set screw threaded through the fixed member and adapted to engage the stud, and a movable section movable vertically with respect to the fixed section, said sections having engaging ribs and grooves 60 for constraining them to hold a definite position with respect to each other during adjustment, means for clamping the sections together, the fixed section having oppositely arranged outwardly extending guides or 65 ways, and having a stop at the lower end

of each guide or way, a guide member for the brush having means for detachably securing a brush thereto, said guide member having overlying flanges for engaging behind the guides, the guide member being 70 mounted to slide toward and from the commutator bars, a resilient member supported by the movable sections of the holder adjacent to the guide member, means for varying the tension of the said resilient member, the resilient member normally acting to force the guide member toward the commutator bars, the guide member having a threaded opening, and a set screw passing through the brush and engaging the opening, a connector held to the brush by the 75 said screw, a connector held detachably on the body of the fixed sections, and an insulated conductor connecting the two connectors.

3. A commutator brush holder, comprising a fixed member having a transverse opening for receiving a supporting stud for the holder, a set screw threaded through the fixed member and adapted to engage the 80 stud, and a movable section movable vertically with respect to the fixed section, said sections having engaging ribs and grooves for constraining them to hold a definite position with respect to each other during 85 adjustment, means for clamping the sections together, the fixed section having oppositely arranged outwardly extending guides or ways, and having a stop at the lower end of each guide or way, a guide 90 member for the brush having means for detachably securing a brush thereto, said guide member having overlying flanges for engaging behind the guides, the guide member being mounted to slide toward and from the 95 commutator bars, a resilient member supported between the side members adjacent to the guide member, means for varying the tension of the said resilient member, a connection between the resilient member 100 and the guide member, the resilient member normally acting to force the guide member toward the commutator bars.

4. A commutator brush holder, comprising a fixed section for attachment to a support, and a movable section adjustable vertically with respect to the fixed section, each section consisting of a body and wings extending laterally from the body in parallel spaced relation, the wings of the movable 115 section fitting between the wings of the fixed section, said wings having interengaging ribs and grooves for guiding them during adjustment, means for clamping the sections together, each wing of the movable 120 section extending beyond the adjacent wing of the fixed section and having an outwardly extending flange provided at its lower end 125 with a stop.

5. A commutator brush holder, comprising 130

ing a fixed section for attachment to a support, and a movable section adjustable vertically with respect to the fixed section, each section consisting of a body and wings extending laterally from the body in parallel spaced relation, the wings of the movable section fitting between the wings of the fixed section, said wings having interengaging ribs and grooves for guiding them during adjustment, means for clamping the sections together, each wing of the movable section extending beyond the adjacent wing of the fixed section and having an outwardly extending flange, a guide member for the brush, and comprising a plate having at each end an overlying flange for engaging the opposite face of the adjacent guide from the plate, a coil spring supported between the wings, and a connection between the spring and the guide member.

6. A commutator brush holder, comprising a fixed section for attachment to a support, and a movable section adjustable vertically with respect to the fixed section, each section consisting of a body and wings extending laterally from the body in parallel spaced relation, the wings of the movable

section fitting between the wings of the fixed section, said wings having interengaging ribs and grooves for guiding them during adjustment, means for clamping the sections together, each wing of the movable section extending beyond the adjacent wing of the fixed section and having an outwardly extending flange, a guide member for the brush, and comprising a plate having at each end an overlying flange for engaging the opposite face of the adjacent guide from the plate, a coil spring supported between the wings, and a connection between the spring and the guide member.

7. A commutator brush holder, comprising a fixed section for attachment to a support, and a movable section mounted for vertical movement on the fixed section, means for clamping the sections in adjusted position, a guide member for a brush mounted to slide on the movable section of the holder toward and from the commutator, and resilient means normally acting to press said guide member toward the commutator.
